UNITED STATES PATENT OFFICE.

HENRY BOUNDS CARY, OF LOS ANGELES, CALIFORNIA, ASSIGNOR OF ONE-HALF TO
ARPA W. FROST, OF LOS ANGELES, CALIFORNIA.

WORD-COUNTING ATTACHMENT FOR TYPE-WRITING MACHINES.

1,265,174.

Specification of Letters Patent.

Patented May 7, 1918.

Application filed October 25, 1916. Serial No. 127,724.

To all whom it may concern:

Be it known that I, HENRY BOUNDS CARY, a citizen of the United States, residing at Los Angeles, in the county of Los Angeles and State of California, have invented certain new and useful Improvements in Word-Counting Attachments for Type-Writing Machines, of which the following is a specification.

10 This invention relates to a word counting attachment for typewriting machines and particularly to an attachment of this kind which is especially adapted for counting the words and characters of telegrams and similar messages written on typewriters.

The principal object of the present invention is to provide a device which is readily attachable to a typewriting machine and which will automatically count and register 20 on a suitable device the number of words and characters counting as words which have been written by the machine to which the device is attached.

Another object is to provide a device 25 which will positively register every word and character counting as a word whether in the upper or lower case of the typewriter keyboard.

Another object is to provide a counting 30 mechanism which will count the words in groups of 50 each, the letter type of night messages being at present charged for on the basis of a minimum rate of 50 words or less.

35 Another object of the invention is to provide a counting and registering mechanism which requires but a small amount of power to operate it, in order that the additional effort will be hardly noticeable to the operator of the machine to which the mechanism is attached.

The above and other objects and the novel features of the invention will be apparent 45 from the following description taken in connection with the accompanying drawings, in which similar reference characters indicate the same parts in the several figures of the drawings.

In the drawings:

50 Figure 1 is an inverted plan view of a typewriting machine showing the word counting attachment mounted in place thereon;

Figs. 2 and 3 are transverse sectional view 55 of the attachment taken on Fig. 1 on the

lines II-II and III-III, respectively, with the machine in an upright position;

Fig. 4 is a vertical sectional view of the mechanism taken on the line IV-IV of Fig. 1;

Fig. 5 illustrates the side of the registering mechanism opposite to that shown in Fig. 4, parts of the casings being removed to disclose the interior;

Fig. 6 is a front view of the registering 65 mechanism and its operating means;

Fig. 7 is a cross-sectional view of the registering mechanism, taken on the line VII-VII of Fig. 4;

Fig. 8 is a top view of the casing of the 70 registering wheels, a part of the casing being omitted;

Figs. 9 to 14, inclusive, are perspective 75 views of elements of the registering mechanism, and

Fig. 15 is a sectional view of the mounting of the registering wheels, taken on the line XV-XV of Fig. 4.

Referring to Figs. 1 to 6 in particular, 80 20 and 21 are base bars having holes extending therethrough to receive screws 22 which rigidly connect the attachment to the bottom of the typewriting machine M. Adjustable bearing blocks 23 are mounted in the bars 20 and 21 and support a fulcrum 85 rod 24 at its ends, the rod 24 being held in place by the set screws 25 and adjustable by the screws 26 which adjust the blocks 23 vertically in the blocks 20 and 21.

Two frames, W and C, are rockably 90 mounted on the fulcrum rod 24, the frame W being rockable by the key levers of alphabet characters and the frame C being rockable by the levers of other keyboard characters which count as words. The attachment shown is particularly designed to count the words and characters of telegrams, especially lengthy day or night letters. In such messages all the characters, punctuation marks, etc., count as words and this mechanism is designed to register them, so that they will be included in the total number of words, etc., to be charged for.

The frame W consists of two side bars 271 and 272 connected together at their ends by 105 the front and rear bars 273 and 274 respectively. The rear bar 274 is depressible by the lever which causes the printing of the first letter of each word, and a friction spring 275 mounted on the rod 24 engages 110

against the side bar 272 and holds the frame in its depressed position until the spacing bar S is depressed or until the frame C is rocked. The front bar 273 is depressed 5 when the spacing bar is operated and this restores the frame W to its normal position. The word is thus registered on the counting mechanism when the first letter thereof is struck. Movement of the frame W along 10 the rod 24 is prevented by collars 28 secured to the rod 24 by set screws.

The frame C consists of two side bars 291 and 292 which have one end pivoted on the rod 24 and at their rear ends they are connected by a back bar 293. The back bar 293 is capable of being engaged by any one of the levers of the keyboard characters other than the alphabet key levers, and when thus actuated, the mechanism connected to the 15 frame C will register the written character as a word. The upper edges of both the back bars 274 and 293 are notched as indicated in Figs. 2 and 3, so that the frames W and C will only be rocked by the levers intended to 20 operate them. A spring 294 has one end coiled around the fulcrum rod 24 and secured to the adjustable ratchet collar 295 by means of which the tension of the spring may be changed. The other free end of this 25 spring extends outwardly at right angles to the rod 24 and beneath a crossbar 296 on the frame C, exerting an upward pressure to restore the frame C to its normal position immediately after each depression of said 30 frame.

The back bar 274 of the frame W is connected to the outer end of a crank arm 30 and the inner end of the arm 30 is secured to a U-shaped rocker plate 31. The plate 31 has a part 311 which extends beneath the base bar 21, and the parallel parts 312 are pivotally supported on the fulcrum rod 24 at opposite sides of the base bar 21. The outer side of the rocker plate 31 has an upwardly 35 extending bar 32 adjustably secured thereto by screws 321. A dog 33 is pivoted at the upper end of the bar 32 and has a lateral extension 331 adapted to engage one of the fifty pins 34 on a wheel A which constitutes 40 part of the registering mechanism to be described. A spring 332 on the bar 32 holds the dog 33 in such a position that when the back bar 274 of the frame W is struck and depressed by an alphabet key lever, and the 45 bar 32 is rocked, the extension 331 will engage a pin 34 and rotate the wheel A one-fiftieth of a turn.

The back bar 293 of the frame C is connected to the outer end of a crank arm 35 60 and the inner end of the arm carries a U-shaped rocker plate 36 which has its sides 361 pivoted on a rod 37 extending through the base bar 21. The outer side of the rocker plate 36 has a bar 38 secured to it and a bill-shaped dog 39 is pivoted at the upper end of

the bar 38. A spring 391 is connected to the dog and secured to the bar 38 and holds the dog in such a position that when the bar 38 is rocked by the depression of the frame C the bill engages a pin 34 and rotates the 70 wheel A one-fiftieth of a turn. When the frame and bar are retracted the spring 391 permits the bill to ride up over the next pin below it and move back out of the path of the pins. 75

A bracket 40 is rigidly secured to the base bar 21 and extends upwardly and outwardly therefrom. A guiding element 41 is secured to the bracket and is provided with notches 411 to receive and guide the bars 32 and 38. 80 The registering mechanism is also mounted on the bracket 40.

The registering mechanism comprises a circular casing 42 in which are mounted the two independently rotatable registering 85 wheels A and B. The casing 42 has a stem 421 secured to its lower side, the stem being provided with a slot 422 to receive screws 401 on the bracket, whereby the casing and the parts thereon may be adjusted at the 90 exact height desired. The side of the casing facing the machine is open to permit the removal of the parts therefrom, but the side away from the machine is closed. The casing also has two sight openings 423 and 424 95 in its periphery and at the front side to expose portions of the wheels A and B within.

A partition 43 is located inside the casing 42 and has a notch 431 which fits a lug 425 on the casing to properly assemble, and lock 100 these parts together against rotation, but permit the removal of the partition and parts thereon. The partition has two hubs or bosses 432 and 433 on opposite sides of its center and also a bore through both bosses 105 to receive a stem or shaft 44 integral with the spider arms 441 which carry the rim 442 of the wheel A. A nut 443 engages the threaded outer end of the stem 44 to hold it in place. The partition is also secured to the casing 42 by a nut 434 which engages a threaded part of the hub 433. The two wheels A and B are thus coaxially mounted on opposite sides of the partition in the 110 casing. 115

The rim of wheel A has fifty parallel pins extending from one face thereof and the peripheral side of the rim has a series of numbers 0 to 49 thereon, visible in succession through the window 423. It requires fifty 120 successive steps of the wheel A to turn it a complete revolution. By mechanism to be described each complete revolution of wheel A causes wheel B to move up one step and show an additional 50 at the window 424, since the periphery of the wheel B is provided with a series of numbers beginning with 0 and rising in steps of 50 to 2450. The operation of bars 32 and 38 moves the wheel A one step at a time which is equal to the 130

registering of one word or character at a time.

In order to prevent the mechanism registering more than one word at a time, a 5 double-nosed compound pawl is employed, the pawl consisting of two members 45 and 46. The member 45 is pivoted at 461 on the member 46 and has two points 451 and 452 which alternately engage the pins 43 10 when the registering wheel A is rotated. The point 451 prevents the return of the wheel and the point 452 prevents more than one pin passing a given point at each stroke of the actuating members 32 and 38. The 15 member 46 of the compound pawl is pivoted on a pintle 471 mounted on a bracket 47 carried on the upper outer side of the casing 42, and has a forwardly extending tail provided with an integral lateral extension 462 20 which projects beneath the finger lever 48 also pivoted on the pintle 471. When the finger lever is manually depressed the pawl member 46 will be turned which in turn causes the member 45 to be lifted bodily 25 to raise its points 451, 452 out of the path of the pins 34. The member 45 has a slot 453 through which the pintle 471 passes, and the head of the pintle holds this member in place but allows the rear end of it 30 to move freely. The finger lever 48 has an integral pawl finger 481 the outer free end of which extends through a hole 426 in the casing 42 and is adapted to successively engage the holes 49 in the rim of the wheel 35 B to hold that wheel in the position in which it is moved by every complete revolution of the wheel A. A spring wire extends around a button 427 on the casing and below the pintle 471, and the free ends 50 40 and 501 thereof bear upon the upper edges of the pawls 45 and 481 to yieldingly hold those members in engagement with the wheels A and B.

The pawls, brackets and part of the finger lever are inclosed by a small cap or casing 51 which has a bifurcated part 511 at the rear end engaging a headed button 512 on the casing 42. A cross bar 513 at the front end engages under a resilient latch 514 50 which consists of an integral part of the bracket extending forwardly and folded on itself to form a catch under which the edge 513 may be passed. The end of the finger lever 48 projects through the opening 515 55 in the casing 51 and by depressing this lever the pawls 45 and 481 will be raised and release the wheels A and B so that the latter may restore to their zero positions.

As the register wheel A is rotated by the 60 actuating bars 32 and 38, it stores energy in a spiral retracting spring wire 52 which is set in a cup-shaped cam 53 which turns freely on the hub 432, see Fig. 15. The ends of the spring 52 are respectively secured to 65 the cam 53 and to one of the spokes 441

of the wheel A. When the wheel A is turned, restoring energy will be stored in the spring, the cam 53 being provided with a projection forming a tooth 531 which is engaged by the end of the arm 541 of a 70 double-armed cam tripping lever 54 pivoted at 542 on the partition 43. When the total number of words and characters registered by the wheel A is less than fifty, as for instance in a case where the total number of 75 words and characters registered is twenty-eight, the spring 52 will have enough energy stored therein to return the wheel A to its zero position when the finger lever 48 is depressed to release the wheel A. 80

A second spiral restoring spring 55 surrounds the hub 433 and has one end 551 secured to the hub and the other end 552 hooked around a spoke of the wheel B. Energy is stored in the spring 55 as the 85 wheel B is rotated by the wheel A, and this spring will return the wheel B to its zero position when the finger lever 48 is depressed. The depression of the lever 48 permits both restoring spring 52 and 55 to 90 operate and simultaneously return the wheels A and B to their zero positions. The stop 56 on the wheel B (see Fig. 5) engages the stop 57 on the partition to limit the return movement of the wheel B. 95

Each time the wheel A makes a complete revolution its restoring spring 52 is released by the movement of the trip arm 541 out of engagement with the cam tooth 531, see Fig. 4. The cam 53, when released, is rotated 100 one complete revolution by the spring 52 and in the meantime the end of the trip arm 541 is returned by the spring 58 to a position to engage the cam tooth 531 and lock the cam against turning so that energy may 105 again be stored in the spring 52.

The arm 541 is one part of a double-armed member 54 having a pivot opening 543, see Figs. 4, 5 and 12. The other part of the member 54 has two arms 544 and 545, the former being approximately parallel to the arm 541 and carrying the rockable member 59. A pivot pin 595 passes through the holes 546 and 591 in the arm 544 and member 59, respectively. A trip finger or catch 60, see 115 Figs. 4 and 13, slides along one face of the arm 545 and the shank of a stud 601 passes through the holes 592 and 602 of the rocking member 59 and finger 60, to pivotally connect them together. The connecting pin 601 120 passes through a slot 547 in the arm 545 and another stud 548 is secured in the hole 549 in the outer end of the arm 545 and passes through a slot 603 in the trip finger 60. This connection of the trip finger 60 to the 125 arm 545 permits the finger to freely slide back and forth along the arm. The heads of the studs 601 and 548 hold the finger in place. A hook 604 on the outer end of the finger 60 is engaged by a tripping pin 61 130

on the inner side of the flange 442 of the wheel A, and this pin raises the trip finger 60, and rocks the double-armed member 54, throwing the arm 541 out of engagement with the face 531 of the cam tooth 532, allowing the cam tooth 532 to rotate and release the stored energy in the spring 52. During the rotation of the cam tooth 532, its face 531 strikes and momentarily engages a projection 593 on the upper end of the rocker 59 and rocks the latter. This striking action of the face 531 against the projection 593 pulls the trip finger 60 inwardly toward the pivot 542 a sufficient distance to draw the hook 604 of the finger out of the way of the pin 61 on the wheel A. The pin 61 moves past the trip finger 60 just as the fiftieth word is counted and then the finger 60 is immediately returned to its normal position by the spring 58. This spring is coiled around the pivot 542 and has one end hooked around the edge of the opening 433 in the partition, as at 581, and the other end is hooked over the hook 594 on the rocker 59, exerting a yielding turning force on the rocker tending to push the trip finger 60 outwardly so that the hook of the finger will normally be in the path of the tripping pin 61 on the wheel A.

The momentary arresting of the rotation of the cam tooth 532 by its face 531 striking the projection 593 at the upper end of the rocker 59, as above explained, is also for the purpose to allow and give sufficient time to permit the upper end of the arm 541 to return to its normal position, as shown in Fig. 4, and be again engaged by the face 531 of the tooth cam 532, the acceleration of which has thus been checked before said cam tooth 532 and its face 531 rotates back to its normal position, shown in Fig. 4, after the cam tooth 532 has been released from engagement with the upper end of the arm 541.

Just as the fiftieth word or character is registered by the wheel A, the tripping pin 61 thereon engages the arm 63 of a double-armed actuating or advancing device which straddles a bracket 435 which is a part of the partition 43 and projects into the opening therein. The actuating device is pivoted on the pin 631 on said bracket, see Figs. 4, 5 and 9, and consists of a single piece of sheet metal doubled to provide two parallel arms 63 and 64, one arm 63 being located on the same side of the partition with the wheel A and the other arm 64 being located on the side of the partition with the wheel B. The lower end of the arm 64 has an advancing pawl 65 pivoted thereon, which pawl is engaged below its pivot 651 by the lower end of a spring wire 66 which tends to throw the pawl into line with the arm 64 and also so that the upper end of the pawl will engage the stop 642 on the

arm 64. In that position the lower end 652 of the pawl 65 drops into engagement with the inner end of one of the holes 49 in the wheel B and a still further movement of the actuating device moves the wheel B forward one step which is equivalent to a complete revolution of the wheel A and the next higher multiple of fifty will be exposed at the window 424 of the casing 42.

The arm 63 is adjusted so that the point 632 thereof will pass over the tripping pin 61 when the wheel A completes its fiftieth step. The free end of a spring 67 presses against the arm 63. One end of the spring 67 is hooked in a notch 633 in one edge of the arm 63 and the other end is coiled around the hub 433 and fastened thereto as at 671, see Figs. 4, 5 and 15. The spring 67 serves to return the advancer or actuator to its normal position, shown in Fig. 5, pushing the lower end of the pawl 65 against a stop 68 which lifts the point of the pawl out of the way of the wheel B, so that if the latter should be released the pawl would not prevent the restoration of the wheel B to its zero position. The stop 68, see Figs. 5 and 11, consists of a bar having a slot 681 at one end to receive a pin 682 whereby the stop is secured in any desired adjusted position. The forward end of the bar is bent as at 683 so as to form the equivalent of a pin in the path of the pawl 65.

A limiting device 69 is pivoted at 691 on the partition 43 and is free to swing on its pivot so that normally the end of the arm 692 at the lower end of the device lies against the projection 642 on the arm 64 of the advancing member. When the advancer is swung forward to the left in Fig. 5 the tooth 693 on the limiting device is swung into one of the holes 49 on the wheel B just at the moment that the advancer reaches the end of its stroke. This serves to prevent an overthrow of the wheel B and keeps it from moving forward more than one step at a time. The pin 57 on the partition 43, also serves as a stop for the limiting device 69. The member 69 is so hung that gravity will immediately restore it to its normal position, as in Fig. 5, when the advancer is returned to its normal position by the spring 67.

As heretofore explained, each step which the wheel B is advanced causes the spring 55 to be wound up a slight amount and the pawl or catch 481 locks the wheel B in its successive positions, but when this pawl is lifted by depressing the finger lever 48, the spring 55 will act and retract the wheel B to its zero position, that is, until the pin 56 engages the pin 57. This same depression of the finger lever 48 also permits the spring 52 to restore the wheel A to its zero position, so that both wheels will be ready for counting the words of another message. The total number of words and characters in the mes-

sage written equals the sum of the readings registered by the two wheels.

While I have shown and described my invention as applied to counting words of a telegram printed by a typewriter, said counter mechanism, as will be easily understood from its construction and operation, may be employed and is readily adapted for other and varied purposes and in conjunction with other mechanisms, as, for example, recording mileage traveled by automobiles and other vehicles, number of messages sent over a telephone, sales made by an individual salesman or total number of sales in a department store, recording repeated operations of special machines used in manufacturing of pieces during a given period of time, and in fact any other purpose that demands a record performance of certain operations, in a given time, and I wish it to be distinctly understood that my invention has been devised and is intended to include such broad and general scope.

What I claim is—

of said fixed number of words, and means for releasing the energy stored in said spring and momentarily arrest its action each time the second registering device is actuated by the first.

3. In a word counting attachment for typewriting machines, the combination of actuating means operable by key levers of alphabet and keyboard characters of the upper and lower case of a typewriting machine, a registering device operable by said actuating means to count up to and including a fixed total number of words and characters, a restoring spring for said device adapted to have energy stored therein as said device is actuated, means for releasing said spring to permit it to restore said device to its zero position when the total number of words registered on said device is less than said fixed number, a second registering device, means operable by the first registering device to register multiples of said fixed number of words, means for automatically releasing the energy stored in said spring and momentarily arrest its action each time the second registering device is actuated by the first, a second spring for restoring said second registering device and adapted to have energy stored therein as said second device is actuated, and means for releasing said second spring to permit it to return the second registering device to its zero position.

4. In a word counting attachment for typewriting machines, the combination of actuating means operable by key levers of alphabet and keyboard characters of the upper and lower case of a typewriting machine, a registering device operable by said actuating means to count up to and including a fixed total number of words and characters, a restoring spring for said device adapted to have energy stored therein as said device is actuated, means for releasing said spring to permit it to restore said device to its zero position when the total number of words registered on said device is less than said fixed number, a second registering device, means operable by the first

25 1. In a word counting attachment for typewriting machines, the combination of actuating means operable by key levers of the alphabet and keyboard characters of the upper or lower case of a typewriting machine, a registering device operable by said actuating means to count up to and including a fixed total number of words or characters or both, a second registering device connected with and operable by the first device to register multiples of said fixed number of words, means guarding said first registering device to prevent the actuating means registering more than one word or character at a time and also preventing the return of said first registering device to its zero position, means guarding said second registering device to prevent the return of the latter to its zero position, means for restoring said devices to their zero positions, and means for releasing both of the guarding means to permit said restoring means to return the devices to their zero position.

2. In a word counting attachment for typewriting machines, the combination of actuating means operable by key levers of the alphabet and keyboard characters of the upper and lower case of a typewriting machine, a registering device operable by said actuating means to count up to and including a fixed total number of words and characters, a restoring spring for said device adapted to have energy stored therein as said device is actuated, means for releasing said spring to permit it to restore said device to its zero position when the total number of words registered on said device is less than said fixed number, a second registering device, means operable by the first registering device to cause the operation of the second registering device to register multiples of said fixed number of words, means for automatically releasing the energy stored in said spring each time the second registering device is actuated by the first, a second spring for restoring said registering device and adapted to have energy stored therein as said second device is actuated, means for releasing said second spring to permit it to return the second registering device to its zero position, and means for simultaneously operating both said releasing means at will to restore both devices of the registering mechanism to zero position.

5. In a word counting attachment for typewriting machines, the combination of a rotary register wheel carrying a series of pins engageable by operating means whereby the wheel is rotated, means actuated by the keys of the typewriter for engaging said series of pins, means whereby said wheel may be retracted to its zero position when it has moved less than a predetermined amount, a pawl having two points adapted to move into the path of said pins alternately, one to prevent the unintended retraction of the wheel and the other to prevent more than one step of said register wheel at a time, and a finger lever whereby the pawl may be lifted out of the path of said pins to permit the return of the wheel to its zero position.

6. In a word counting attachment for typewriting machines, the combination of a rotary register wheel carrying a series of pins engageable by operating means whereby the wheel is rotated, means actuated by the keys of the typewriter for engaging said series of pins and rotating said wheel one step at a time, means whereby said wheel may be retracted to its zero position when it has moved less than a predetermined amount, a pawl having two points adapted to move into the path of said pins alternately, one to prevent the unintended retraction of the wheel and the other to prevent more than one step of said register wheel at a time, a pintle, a plate pivoted between its ends on said pintle, said pawl being pivoted between the points thereof on one free end of said plate and also having a slot through which said pintle extends, and a finger lever adapted to engage the other free end of said plate to rock the plate and bodily lift said pawl to move the points thereof out of the path of the pins on said wheel.

7. In a word counting attachment for typewriting machines, the combination of two rotary register wheels, the first register wheel carrying a series of pins engageable by operating means actuated by the keys of the typewriter and the second wheel having a series of holes engageable by the operating means controlled and moved by the first register wheel, means whereby each wheel may be retracted to its zero position, means engaging said pins to prevent the unintended retraction of the first wheel or the movement of more than one step at a time by said operating means, means engaging said holes to prevent the retraction of the second wheel, and a device operable at will to simultaneously raise said engaging means out of the paths of said pins and holes respectively to permit the return of the wheels to their zero positions.

8. In a word counting attachment for typewriting machines, the combination of

two register wheels, the first register wheel carrying a series of pins engageable by operating means actuated by the keys of the typewriter and the second wheel having a series of holes engageable by operating means controlled and moved by the first register wheel, means whereby each wheel may be retracted to its zero position, means engaging said pins to prevent the unintended retraction of the first wheel or the movement of more than one step at a time by said operating means, means engaging said holes to prevent the retraction of the second wheel, spring means holding both said engaging means in the pins and holes, a finger lever operable at will to simultaneously raise the engaging means out of the paths of said pins and holes to permit the return of said wheels to their zero positions, and a casing inclosing said engaging means and spring and leaving only the outer free end of the finger lever uninclosed.

9. In a word counting attachment for typewriting machines, the combination of a casing, a stationary partition in said casing having bosses on opposite sides thereof and a bore extending through the bosses, a rotary register wheel having a central shaft fixed thereon and extending into said bore, means actuated by the keys of the typewriter to rotate said register wheel one step at a time, means for locking said wheel at any of its rotated positions, a retracting spring surrounding the boss adjacent said wheel and adapted to restore said wheel to its zero position when it is released, a second rotary register wheel mounted on the other boss, means pivotally supported on said stationary partition and actuated by the first wheel adapted to engage said second wheel at each complete rotation of the first register wheel, and a second retracting spring surrounding said other boss and adapted to restore said second wheel to its zero position when it is released.

10. In a word counting attachment for typewriting machines, the combination of a casing, a stationary partition in said casing having bosses on opposite sides thereof and a bore extending through the bosses, a rotary register wheel having a central shaft fixed thereon and extending into said bore, means actuated by the keys of the typewriter to rotate said register wheel one step at a time, means for locking said wheel at any of its rotated positions, a retracting spring surrounding the boss adjacent said wheel and adapted to restore said wheel to its zero position when it is released, a second rotary register wheel mounted on the other boss, said partition having an opening therethrough, an actuating device mounted on said partition and extending through said opening in the partition, means on the first wheel for operating said device, means on

the second wheel engageable by said device to cause a partial rotation of said second wheel on each complete rotation of the first wheel, and a second retracting spring surrounding said other boss and adapted to restore said second wheel to its zero position when it is released.

11. In a word counting attachment for typewriting machines, the combination of a rotary register wheel, means constructed and arranged to be operated by the keys of the typewriter to rotate said register wheel one step at a time in one direction, a retracting spring adapted to be wound and have energy stored therein as the wheel is rotated, a toothed member attached to one end of the spring, a trip normally engaging the tooth of said toothed member to hold it while energy is being stored in said spring, and means on said register wheel whereby said trip is operated after a predetermined movement of said wheel to release said toothed member and spring to expend the energy in the spring without retracting the wheel.

12. In a word counting attachment for typewriting machines, the combination of a rotary register wheel, means constructed and arranged to be operated by the keys of the typewriter to rotate said register wheel one step at a time in one direction, a retracting spring adapted to be wound and have energy stored therein as the wheel is rotated, a toothed member attached to one end of the spring, a trip normally engaging the tooth of said toothed member to hold it while energy is being stored in said spring, means on said wheel whereby said trip is operated after a predetermined movement of said wheel to release said toothed member and spring to expend the energy in the spring without retracting the wheel, and means for resetting said trip in engagement with said toothed member after the release of the energy in the spring to permit energy to be again stored in the spring upon further movement of the wheel.

13. In a word counting attachment for typewriting machines, the combination with a rotary register wheel, means constructed and arranged to be operated by the keys of the typewriter to rotate said wheel one step at a time in one direction, a retracting spring adapted to be wound and have energy stored therein as the wheel is rotated, a toothed member attached to one end of the spring, a double-armed trip lever having means on one arm normally engaging the toothed member to hold it while energy is being stored in said spring, and a slidable trip finger on the other arm engageable by a pin on said wheel upon a predetermined movement of the wheel and adapted to be momentarily engaged by said toothed member to release the toothed member and spring to expend the energy in the spring without

retracting the wheel and permit the pin on the wheel to pass beyond the slidable trip finger.

14. In a word counting attachment for typewriting machines, the combination of a rotary register wheel, means constructed and arranged to be operated by the keys of the typewriter to rotate said register wheel one step at a time, a retracting spring adapted to be wound to store energy therein as the wheel is rotated, a member secured to the spring and carrying a projection, a double-armed trip having means on one arm normally engaging said member to hold it while energy is being stored in said spring, a slidable finger on the other arm engageable by a part on said wheel to throw the means on the first mentioned arm out of engagement with said member, a device carried by said trip and momentarily engageable by the projection on said member to move the means on said other arm out of the path of said part on the wheel, and means for resetting said double-armed trip to permit energy to be again stored in said spring upon further movement of said wheel.

15. In a word counting attachment for typewriting machines, the combination of a rotary register wheel, means constructed and arranged to be operated by the keys of the typewriter to rotate said register one step at a time, a retracting spring adapted to be wound to store energy therein as the wheel is rotated, a member secured to the spring and carrying a projection, a double-armed trip having means on one arm normally engaging said member to hold it while energy is being stored in said spring, a slidable finger on the other arm engageable by a part on said wheel to throw said means on the first-mentioned arm out of engagement with said member, a pivoted device carried by said trip and connected to said finger, said device being engageable by the projection on said member to move the finger out of the path of said part on the wheel and at the same time momentarily arrest the movement of said member and its projection, and means for resetting the trip and parts associated therewith.

16. In a word counting attachment for typewriting machines, the combination of two rotary register wheels, means constructed and arranged to be operated by the keys of the typewriter to rotate the first of said register wheels one step at a time, means whereby the first register wheel may be retracted when it has moved an incomplete revolution, a trip for releasing the retracting means upon the completion of a predetermined movement by said first wheel, means actuated by the first wheel for operating said second wheel when the first wheel completes its revolution, a fixed support between said

wheels for said trip and operating means for the second wheel, a projection on the first register wheel for actuating the trip and operating means in their normal positions.

- 5 17. In a word counting attachment for typewriting machines, the combination of two rotary register wheels, means constructed and arranged to be operated by the keys of the typewriter to rotate the first of said register wheels one step at a time, the second wheel having a series of recesses, a pivoted pawl having a part for successively engaging said recesses to advance said second wheel, a double-armed rockable member carrying said pawl, means on the first wheel to engage one of the arms of said rockable member to cause the pawl to advance said second wheel, and means for withdrawing said part of the pawl from engagement with the recesses of the second wheel.
- 10 18. In a word counting attachment for typewriting machines, the combination of two rotary register wheels, means constructed and arranged to be operated by the keys of the typewriter to rotate the first of said register wheels one step at a time, a support upon which both wheels are rotatably mounted, said support having an opening therein and a bracket extending
- 15
- 20
- 25

into the opening, a rockable member mounted on said bracket and extending through said opening and terminating in arms on both sides of the support, means on the first wheel for rocking said member, and means on said rockable member arranged and constructed to engage and advance the second wheel when said rockable member is rocked.

19. In a word counting attachment for typewriting machines, the combination of a casing, a register wheel rotatably mounted in the casing and having a series of holes in its periphery, a device pivoted within the periphery of the wheel and operable to engage the inner ends of said holes to advance said wheel, means constructed and arranged to be operated by the keys of the typewriter to actuate said pivoted device within the periphery of the wheel, a retracting spring in the casing for restoring said wheel to its zero position, a releasable device engaging the outer ends of said holes to prevent the return of said wheel to its zero position, and means for operating said releasable device at will to permit the retracting spring to return the wheel to zero position.

In testimony whereof I hereby affix my signature.

HENRY BOUNDS CARY.
